CLAIM

I claim the ornamental design of a reading lamp, as shown and described.

DESCRIPTION

FIG. 1 is a side perspective view of a reading lamp in an upright position with the lamp arm in an extended position, showing my new design;

FIG. 2 is a left side view of the reading lamp as shown in FIG. 1;

FIG. 3 is a right side view of the reading lamp as shown in FIG. 1;

FIG. 4 is a front view of the reading lamp as shown in FIG. 1;

FIG. 5 is a rear view of the reading lamp as shown in FIG. 1;

FIG. 6 is a top plan view of the reading lamp as shown in FIG. 1;

FIG. 7 is a bottom plan view of the reading lamp as shown in FIG. 1;

FIG. 8 is another bottom plan view of the reading lamp as shown in FIG. 1, with an alternate configuration of the broken line connection portion in FIG. 7;

FIG. 9 is a side perspective view of the reading lamp as shown in FIG. 1, in an upright position with the lamp arm in an extended position and rotated towards the perspective side;

FIG. 10 is a side perspective view of the reading lamp as shown in FIG. 1, in an upright position with the lamp arm in an extended position and rotated away from the perspective side; and,

FIG. 11 is a side perspective view of the reading lamp as shown in FIGS. 1-8, in an upright position with the lamp arm in a collapsed position.

The oval-shaped feature depicted on the bottom of the arm in FIGS. 7-10 depicts a surface feature being a boundary of a light source of the reading lamp.

(Continued)

Broken line portions of the Figures are for illustrating certain surface features of the reading lamp and form no part of the claimed design.
